UNITED STATES PATENT OFFICE

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS

WASHING MACHINE

Application filed July 5, 1927. Serial No. 203,393.

This invention has reference to improvements in washing machines, and it has for its principal object to improve that type of such machine which includes a centrifugal extractor for extracting the free water from clothes and other materials, used in place of the usual and well known wringer roll mechanism.

One of the objects of the invention is an extractor comprising a rotatable receptacle, in which the clothes and other materials are placed and from which the free water is extracted by centrifugal action; the waste water being discharged from said receptacle at the upper end thereof into a stationary head encircling said receptacle; said head having discharge outlets at different points circumferentially thereof; and in the provision of a troughed pan removably and rotatably carried within said head, adapted to receive the water discharged from said receptacle and having a discharge outlet adapted, when said pan is rotated to be caused to register with one or the other of the outlets in said head, whereby the water may be discharged into different receptacles.

The invention has for a further object to provide a discharge spout coincident with one of the discharge outlets in said stationary head to direct the water, received from the centrifugal receptacle, away therefrom; and further, to provide a drain board or shelf pivotally connected with said head to adapt it to be swung laterally, whereby to discharge water, directed thereto from said head, to different points.

A still further object of the invention, is to provide an imperforate centrifugal receptacle arranged to discharge water from the upper end thereof; to provide a stationary head at the upper end of said head and having suitable water discharge outlets; to provide a troughed pan rotatable in said head and having an outlet adapted to be brought into coincidence with the outlets in said head; to provide a closure for the upper end of said receptacle to rotate therewith, and to provide a support for said closure, said support hingedly connected with said stationary head.

Other and various objects will appear from the description.

That the invention may be more fully understood, reference is had to the accompanying drawing, forming part of the description, 55 illustrating a preferred embodiment of the invention, in which:—

Fig. 1 is a plan view of a washing machine and centrifugal extractor embodying my invention; the washing machine being broken away and a receptacle being shown in part in dotted lines;

Fig. 2 is a side elevation of Fig. 1, the receptacle being omitted and the support for the closure and said closure being shown 65 raised, in dotted lines;

Fig. 3 is a sectional detail as the same would appear if taken on the line 3—3 Fig. 1;

Fig. 4 is a plan view, in section, as the same would appear if taken on the line 4—4 Fig. 70 5, the drain board or shelf being shown by dotted lines in different positions;

Fig. 5 is a vertical sectional view, as the same would appear if taken on the line 5—5 Fig. 1;

Fig. 6 is a plan view, partly in section, of the troughed pan for the stationary head;

Fig. 7 is a detail in perspective of that part of the troughed pan having the discharge outlet, the pan being tilted over;

Fig. 8 is a sectional detail of the head taken at the outlet adapted to discharge water into the washing machine and also showing the troughed pan, the view being as the same would appear at 8—8 Fig. 4, and

Fig. 9 is a view similar to Fig. 8, but showing the pan in a different position.

Like characters of reference denote corresponding parts throughout the figures.

In the drawings, I have shown the centrifugal extracting receptacle 1 as being preferably associated with a washing machine 2; however, it will be understood, that in the carrying out of the invention the washing machine, as such, could be omitted and a different form of receptacle substituted. As shown, the washing machine is provided with an agitator 3 operated from a shaft 4 passing up through the bottom of the tub. The mounting for the receptacle 1, is not shown, 100

but it is shown provided with a shaft 5 connected with the bottom thereof, and said shafts 4 and 5 may be arranged and adapted to receive their power from a common operating means, not shown.

The tub, forming the washing machine is connected with a head frame 6 and said frame is formed or provided with a head 7 which projects laterally from the said frame and tub. This head like the frame is stationary and is preferably annular in cross-section, comprising a base 8 having an annular opening 9 to admit the receptacle 1 which projects therethrough, see Fig. 5, and at preferably diametrically opposite points said base 8 is provided with elongated discharge outlets 10 and 11, see Fig. 4, the wall forming which is sloping or tapered downwardly and inwardly, as at 12, see Figs. 8 and 9, for a purpose to be explained. While I have elected to show these outlets at diametrically opposite points they may be otherwise located and two or more such outlets provided, as occasion may require. An annular outer wall or flange 13 for the head is provided, which is of suitable depth or extends up from the base 8 to a desired height thereabove. To one side of said head is hingedly connected at 14, a closure supporting bar 15, which, when in closed position lies diametrically across the top of said head, see Figs. 1 and 2, and adapted to be locked or secured in such closed position by means of a locking lever 16 fulcrumed to the side of said head.

Removably and rotatably carried within said head 7 is a troughed pan 17, the same normally resting and rotatable on the base 8 of said head, see Fig. 5. Said pan is annular in cross-section, to conform to the annular shape of the head 7, and the cross-section of the body portion of said pan is formed into a U-shaped trough, including the bottom 18, the inner short upstanding flange 19 the concave wall portion of which forms a continuation of the annular opening 9 in the head 7, and an outer upstanding flange 20 lying next adjacent the flange wall 13 of the head and being of substantially the same height and the upper end of said flange 20 is turned inwardly to form an overlying flange 21 and provide an overhanging shed, see Fig. 5 to prevent the splashing of water therefrom as the water is discharged into said pan from the receptacle 1. The inner edge of said flange 21 is formed or provided with a strengthening rib 22 and at suitable points said rib is provided with finger-holds 23, see Figs. 5 and 6 to enable an attendant, by grasping the same to rotate said pan within the head 7 and on the base 8 thereof. The bottom 18 of said pan is formed or provided with an elongated discharge outlet 24, adapted on rotating the pan to be brought coincident with either of the outlet openings

10 or 11 in the base of the head 7, whereby to selectively discharge water from the head 7 into the tub of the washing machine or into a receptacle or receptacles placed alongside the receptacle 1 of the machine. Surrounding the outlet opening 24 in the bottom of the pan 17 and depending from said bottom, is a flange 25, and said flange, when the outlet 24 is coincident with either of the outlets 10 or 11 in the head 7 projects thereinto, in the manner seen in Figs. 5 and 8 and prevents leakage of water from the pan onto the base portion 8 of the head 7. The tapered or sloping walls 12 of the outlets 10 and 11 in the wall 8 of the head 7 permits the flange 25 of the pan to ride up and onto the base portion 8, as the pan is rotated to different positions and to again drop into an outlet opening in said head, when brought into coincidence therewith, as will be understood.

When assembling the parts described, the support 15 is released and raised, when the pan 17 is dropped into the position shown in Fig. 5, permitting the receptacle to be positioned by passing down through the head and pan. Reversing these steps will permit of the disassembly of the parts. The upper end of the receptacle 1 is turned outwardly and downwardly, as at 26, to provide a flange, which normally overlies the inner short upstanding flange 19 of the pan and insures that the water discharged over such flange is directed into the trough portion of said pan. A closure 27 which is revolvably supported from the support 15 is adapted to be brought into impinging relation with the flange 26 of the receptacle to rotate therewith, and said closure around its outer edge is provided with water egress openings or passages 28 through which water discharged by the centrifugal action of the receptacle 1 finds its way to the pan 17 in the head 7.

Depending from the head 7 and coincident with the outlet opening 11 therein is a water discharge spout 29, and pivotally connected with the underside of said head 7 on a vertically disposed stem 30 depending from said head and preferably located in the rear of the spout 29, is a drain board or shelf 31 which extends laterally and in a downwardly inclined position from said head 7. As shown in Fig. 4 this board or shelf may be swung laterally, whereby said board or shelf may be positioned over a receptacle or receptacles positioned alongside said machine or the receptacle 1 thereof. Such an arrangement permits soapy water extracted from clothes or other materials to be returned from the receptacle 1 to the tub of the washing machine, or if rinse or bluing water, the same may be returned to a rinse or bluing receptacle.

I prefer to provide spring clips 32 for yieldingly holding the pan 17 within the head 7. These clips are shown, in Figs. 1 and 3, as being removably attached to the flanged wall

13 of the head and extend radially inwardly overlying and engaging the flange 21 of said pan. While I prefer the use of such clips they may be omitted if desired.

5 It is obvious that when the outlet opening 24 of the pan is coincident with one of the outlet openings of the head 7, that the other opening in said head is sealed, see the position of the pan in relation to the outlet openings in the head, in Fig. 5. Furthermore it will be obvious that the pan may be easily and manually adjusted circumferentially of the head, by an attendant grasping the finger holds 23 on the pan and moving the same to 15 the position desired. The pan, while it has a snug fit in the head is still loose enough to permit the movements heretofore described.

What I claim is:—

1. In combination, a centrifugal extractor, 20 a stationary head at the upper end of the extractor provided with a plurality of discharge outlet openings, a drain board pivotally supported from said head to receive the discharge from one of said outlet openings and adapted 25 for lateral swinging movement to be positioned over a receptacle or receptacles, and a pan rotatable in said head adapted to receive water discharged from said extractor and having a discharge outlet opening adapted to 30 be selectively positioned over one or the other of the openings in said head, whereby to discharge water from said head at different points.

2. In combination, a centrifugal extractor, 35 a stationary head encircling the upper end of said extractor provided with a plurality of discharge outlet openings, water receiving means removably carried and manually and circumferentially adjustable within said head provided with a discharge outlet adapted to 40 be selectively positioned over one or the other of the openings in said head, whereby to discharge water at different points from said head, a closure supporting means hingedly 45 connected with said head, a closure for the upper end of said extractor rotatably carried by said supporting means, said closure and extractor being so related when said closure engages said extractor as to provide water 50 egress openings therebetween, and a drain board movably connected with said head and registering with one of the openings in said head.

3. In combination, a centrifugal extractor, 55 a stationary head encircling the upper end of said extractor provided with a plurality of discharge outlet openings, a spout registering with one such opening and depending from said head, a drain board registering with said spout, means to pivotally support said board from said head, a troughed pan removably carried in said head and manually and circumferentially adjustable in said head and provided with a discharge outlet opening adapted to be selec-

tively positioned over one or the other of the openings in said head, and means permitting manual engagement of the pan for adjusting the same.

4. In combination, a centrifugal extractor, 70 a stationary head encircling the upper end of said extractor provided with a plurality of discharge outlet openings, a spout registering with one such opening and depending from said head, a drain board registering with said spout, means to pivotally support said board from said head, a pan removably carried in said head and manually and circumferentially adjustable in said head and provided with a discharge outlet opening 75 adapted to be selectively positioned over one or the other of the openings in said head, said pan being annular in outline and trough shaped in cross-section with an overlying 80 shed portion and means permitting manual 85 engagement of the pan for adjusting the same.

5. In a centrifugal extractor, an annular stationary head provided with spaced elongated discharge outlet openings, the wall forming which are tapered downwardly and inwardly, a pan manually and circumferentially adjustable in said head having an elongated discharge outlet opening adapted to be brought into register with one or the other of the openings in said head, and a depending flange on said pan surrounding the opening therein adapted to enter the openings in said head and to ride over the tapered walls surrounding said openings when moving said pan circumferentially within the head.

6. In a centrifugal extractor, an immovable head member therefor having a discharge outlet opening and a spout depending therefrom registering with said opening, movable water receiving means in said head and having a discharge outlet opening adapted to be brought into register with the opening in said head, a drain board normally assuming a downwardly inclined position from said head and registering with said spout, and means to pivotally support said board from said head to adapt it to be swung laterally to different positions.

7. In combination, a centrifugal extractor 115 comprising an imperforate receptacle, an approximately shallow chambered head encircling the upper end portion of said receptacle provided with a plurality of discharge outlet openings, a drain board supported from said head to receive the discharge from one of said outlet openings, and a pan rotatable in said head adapted to receive water discharged from over the top of said receptacle and having a discharge outlet opening adapted to be selectively positioned over one or the other of the openings in said head, whereby to discharge water from said head at different points.

8. In combination, a centrifugal extractor 120 comprising an imperforate receptacle, an ap-

proximately shallow stationary chambered head encircling the upper end portion of said receptacle provided with a plurality of discharge outlet openings, a drain board pivotally supported from said head to receive the discharge from one of said outlet openings and normally inclined outwardly and downwardly from said head, and a pan rotatable in said head adapted to receive water discharged from over the top of said receptacle and having a discharge outlet opening adapted to be selectively positioned over one or the other of the openings in said head, whereby to discharge water from said head at different points.

9. In combination, a centrifugal extractor comprising an imperforate tapered receptacle, an approximately shallow chambered head encircling the upper end portion of said receptacle provided with a plurality of discharge outlet openings, a spout registering with one such opening and depending from said head, a drain board registering with said spout and inclined away from said head, a pan removably carried in said head to receive water discharged from over the top of said receptacle and manually and circumferentially adjustable in said head and provided with a discharge outlet opening adapted to be selectively positioned over one or the other of the openings in said head, said pan being annular in outline and trough shaped in cross-section with an overlying shed portion and means permitting manual engagement of the pan for adjusting the same.

10. In combination, a centrifugal extractor comprising an imperforate tapered receptacle, an approximately shallow stationary chambered head encircling the upper end portion of said receptacle provided with a plurality of discharge outlet openings, a spout registering with one such opening and depending from said head, a drain board registering with said spout and inclined away from said head, means to pivotally support said board from said head, a pan removably carried in said head to receive water discharged from over the top of said receptacle and manually and circumferentially adjustable in said head and provided with a discharge outlet opening adapted to be selectively positioned over one or the other of the openings in said head, said pan being annular in outline and trough shaped in cross-section with an overlying shed portion and means permitting manual engagement of the pan for adjusting the same.

11. In combination, a centrifugal extractor comprising a tapered imperforate receptacle arranged for the discharge of liquid over the upper edge thereof, an annular immovable chambered head member encircling the upper end portion of said receptacle and having a plurality of discharge outlet openings, manually movable means in said head

for receiving the liquid discharged from over the top of said receptacle and having a discharge outlet opening adapted to be brought into register with one or the other of said outlet openings in said head, and a drain board normally assuming an inclined position away from said head and registering with one of said outlet openings.

12. In combination, a centrifugal extractor comprising a tapered imperforate receptacle arranged for the discharge of liquid over the upper edge thereof, an annular immovable chambered head member encircling the upper end portion of said receptacle and having a plurality of discharge outlet openings, manually movable means in said head for receiving the liquid discharged from over the top of said receptacle and having a discharge outlet opening adapted to be brought into register with one or the other of said outlet openings in said head, a drain board normally assuming an inclined position away from said head and registering with one of said outlet openings, and means pivotally connecting said board to said head to adapt it to be manually swung to different positions.

13. In combination, a centrifugal extractor comprising a tapered imperforate receptacle arranged to discharge water over the upper edge thereof, a chambered head encircling the upper end of said receptacle provided with a plurality of discharge outlet openings, water receiving means removably carried and manually and circumferentially adjustable within said head provided with a discharge outlet adapted to be selectively positioned over one or the other of the openings in said head, whereby to discharge water at different points from said head, a closure supporting means hingedly connected with said head, a closure for the upper end of said receptacle rotatably carried by said supporting means, closure and receptacle being so related when said closure engages said receptacle as to provide water egress openings therebetween, and a drain board connected with said head and registering with one of said outlet openings therein.

14. In combination, a centrifugal extractor comprising a tapered imperforate receptacle arranged to discharge water over the upper edge thereof, a chambered head encircling the upper end of said receptacle provided with a plurality of discharge outlet openings, water receiving means removably carried and manually and circumferentially adjustable within said head provided with a discharge outlet adapted to be selectively positioned over one or the other of the openings in said head, whereby to discharge water at different points from said head, a closure supporting means hingedly connected with said head, a closure for the upper end of said receptacle rotatably carried by said supporting means, closure and receptacle being so

related when said closure engages said receptacle as to provide water egress openings therebetween, and a drain board movably connected with said head and registering with one of the outlet openings therein.

In witness whereof, I have hereunto affixed my hand this 30th day of June, 1927.

ALPHEUS W. ALTORFER.
